FOCUSING DEVICE FOR INCANDESCENT
STUDIO SPOTLIGHTS

Carl R. Erickson, West Los Angeles, Calif., assignor to Motion Picture Electric Products, Los Angeles, Calif., a corporation of California

Application September 13, 1938, Serial No. 229,682

5 Claims. (Cl. 240—44.2)

This invention relates generally to incandescent spotlights such as are used in motion picture studios for illumination of sets, and more particularly to focusing devices for the incandescent lamp of such spotlights.

Studio spotlights are ordinarily provided with an incandescent lamp that is movable forwardly and rearwardly for focusing purposes. Various focusing devices have been provided for so moving the lamp, such devices usually involving a lead screw, and in all cases of which I am aware, involving a rotatable manual operating member. This rotatable manual operating member is frequently inconvenient to manipulate under conditions as encountered under practical studio conditions. At times the lamp is mounted at a considerable elevation above the floor of the set, on its own stand or a wall bracket, and may therefore not be easy to reach with the hand. The manual focusing member of prior lamps ordinarily extends either from one side or from the back of the lamp. Frequently, the lamp is so situated that the side or the back of the lamp, where the manual focusing member is located, cannot conveniently be reached.

It is accordingly an object of the present invention to provide an improved focusing device for incandescent spotlights, designed to be exceptionally accessible to the operator under all working conditions.

A further object of the invention is to provide a focusing device which can be operated, when the lamp is situated at an elevation such that it cannot be reached by the hand, simply by use of a long stick.

The spotlight of the present invention is provided with a focusing device having two lever arms, which project from the front and from the rear of the lamp casing. These lever arms are simply moved from side to side to accomplish focusing between spot and flood positions. They may readily be engaged and operated by use of a long stick when the lamp is situated at a considerable elevation above the floor. The focusing mechanism is exceptionally simple in character, and is at the same time exceptionally easy to operate and quick to adjust.

The details of the invention will be set forth in the body of the specification, in which is described a present preferred illustrative embodiment thereof. Reference for this purpose is directed to the accompanying drawing, in which:

Fig. 1 is an elevation, partly in section, showing a spotlight embodying the focusing mechanism of the present invention;

Fig. 2 is a horizontal section taken on line 2—2 of Fig. 1; and

Fig. 3 is a rear view of the lower portion of the lamp, showing the focusing mechanism housing and the rear focusing lever arm.

The specific spotlight here shown for illustrative purposes has a substantially cylindrical or barrel-shaped exterior casing 10, provided with forward and rearward openings 11 and 12, respectively. Mounted in forward opening 11 is a conventional lens 13, while rearward opening 12 is closed by a door 14. Secured to the top of the casing is a casting 16 provided with a handle 17. A focusing mechanism housing 20 is mounted on the lower side of the lamp casing. Thus, as illustratively shown in the drawing, housing 20 comprises a casting having arms 21 and 22 engaging the side wall of the casing and secured thereto by screws 23. Housing 20, in the specific form here shown, comprises front and rear walls 25 and 26, respectively, side walls 27, and a bottom wall 28. The lower portion of the lamp casing, inside the boundaries of housing 20, is removed, so that the interior of the lamp opens to the interior of the mechanism housing 20. Of course, while the mechanism housing 20 of the present illustrative form of the invention is shown as comprising a separate casting secured to the lamp casing, it may, if desired, be formed as an integral part of the lamp casing, any mechanical construction being suitable which will provide a proper offset housing spaced or recessed for accommodating the focusing mechanism on or at the lower side of the otherwise substantially cylindrical lamp casing.

The incandescent lamp is designated generally at 30, and its usual socket at 31, the latter being mounted on a platform or carriage 32 provided with perforated lugs 33 and 34 which are slidable on a pair of parallel guide rods 36 running longitudinally of the lamp and mounted at their ends in perforated bosses 38 formed on the forward and rearward walls 25 and 26 of housing 20. Rods 36 are indicated in Fig. 2 as secured in position by means of pins 39 extending through forward bosses 38. As clearly shown, these rods 36 are parallel to the axis of lens 13, and are in a horizontal plane. It will also be noted that incandescent lamp 30 is positioned on the axis of lens 13, and is movable along said axis as platform 32 is moved forwardly or rearwardly along rods 36.

Platform 32 is shown furnished with a bracket 35 supporting a small spherical mirror 37 to the rear of lamp 30. This mirror serves the usual

purpose of receiving light from lamp 30 and reflecting it back and bringing it to a focus at the filament of the lamp.

The improved focusing mechanism for moving lamp 30 along the axis of lens 13 will now be described. A focusing lever 40 is provided, comprising a forwardly projecting arm 41, a rearwardly projecting arm 42, and an intermediate hub 43 pivotally mounted in a suitable manner on lower housing wall 28, as indicated at 43a, at approximately the center of the lamp from front to rear. Extending from hub 43 of lever 40, at right angles to arms 41 and 42, is a third arm 50, and an operative connection is provided between said arm 50 and lamp carriage 32. Though this connection may be embodied in various forms, a simple form is here shown comprising a longitudinal slot 51 in arm 50, and a pin 52 carried by the carriage and engaging in said slot. As here illustratively shown, this pin 52 is set into an arm 53 integral with and projecting laterally from platform 32.

Forward and rearward lever arms 41 and 42 project through horizontal slots 55 and 56, respectively, in the forward and rearward ends of housing 28, being formed on their projecting ends with finger pieces 57 and 58, respectively.

Movement from side to side of either front finger piece 57 or rear finger piece 58 swings lever 43, and therefore arm 50, about pivotal mounting 43a, such movement of arm 50 acting through the described pin and slot connection with the lamp and mirror carriage to cause the latter to be moved along guide rods 36.

The natural friction in the mechanism is such that the carriage will not slide along guide rods 36 as the lamp is tilted forwardly or rearwardly, and will accordingly remain in any position to which it is moved by the focusing mechanism. The leverage of the focusing mechanism is sufficient, however, that the focusing arms may be very easily moved, and may be readily moved, in fact, in cases in which the lamp is out of reach of the hand, simply by engaging a projecting end of the lever with a long stick. The two operating ends of the lever, projecting from the front and rear ends of the lamp, enable the focus of the lamp to be conveniently adjusted, regardless of the position in which it may be situated. Moreover, adjustment of focus may be accomplished with exceptional rapidity. Finally, the focusing mechanism is very simple and inexpensive in construction.

The claims refer to the pivot axis of the focusing lever as being vertical. It is, of course, to be understood that this expression contemplates some deviation from vertical being employed simply to define the general directions of movement of the members. Also, it is to be understood that the lamp will often be employed in tilted positions, in which case the pivot axis would no longer be vertical. The expressions in question of course are not restricted against such tilted positions of use of the lamp, being employed simply for convenience in defining the direction of action of the lever with reference to the lamp as a whole, assuming the lamp to be positioned in a level position as illustrated in the drawing. The expressions employed in the claims are therefore to be regarded as reading on the lamp regardless of the position to which it may be tilted in practice, despite the fact that the pivot axis of the lever will not be vertical in such tilted positions of use.

It is to be understood that while I have now

shown one typical embodiment of the invention, this is for illustrative purposes only, and that various changes in design, structure and arrangement may be made without departing from the spirit and scope of the invention or of the appended claims.

I claim:

1. In an incandescent studio spotlight embodying a lamp casing having an opening at its forward end: a mechanism housing on the bottom of and opening inside said lamp casing, a lamp carriage adapted to support a lamp within said casing, means supporting and guiding said carriage for forward and rearward movement with reference to said lamp casing, a focusing lever within said mechanism housing pivotally mounted on a substantially vertical axis, a slot in a wall of said housing passing said focusing lever, and an operative interconnection between said focusing lever and said lamp carriage.

2. In an incandescent studio spotlight embodying a lamp casing having an opening at its forward end: a mechanism housing on the bottom of and opening inside said lamp casing, a lamp carriage adapted to support a lamp within said casing, means supporting and guiding said carriage for forward and rearward movement with reference to said lamp casing, said mechanism housing having front and rear walls provided with horizontally extending slots, a focusing lever within said housing pivotally mounted on a substantially vertical axis, said lever having oppositely extending arms projecting through said horizontally extending slots, and an operative interconnection between said focusing lever and said lamp carriage.

3. In an incandescent studio spotlight embodying a lamp casing having an opening at its forward end: a mechanism housing on the bottom of and opening inside said lamp casing, a lamp carriage adapted to support a lamp within said casing, means supporting and guiding said carriage for forward and rearward movement with reference to said lamp casing, said mechanism housing having front and rear walls provided with horizontally extending slots, a focusing lever within said housing pivotally mounted on a substantially vertical axis, said lever having oppositely extending arms projecting through said horizontally extending slots, and an operative interconnection between said focusing lever and said lamp carriage embodying a pin and slot.

4. In an incandescent studio spotlight embodying a lamp casing having an opening at its forward end: a mechanism housing on the bottom of and opening inside said lamp casing, a lamp carriage adapted to support a lamp within said casing, means supporting and guiding said carriage for forward and rearward movement with reference to said lamp casing, said mechanism housing having front and rear walls provided with horizontally extending slots, a focusing lever within said housing pivotally mounted on a substantially vertical axis, said lever having oppositely extending arms projecting through said horizontally extending slots, and an operative interconnection between said focusing lever and said lamp carriage embodying a third arm on said lever extending substantially at right angles to said first mentioned arms, and a connection between said third arm and the carriage.

5. In an incandescent studio spotlight embodying a lamp casing having an opening at its forward end: a mechanism housing on the bottom of and opening inside said lamp casing, a lamp

carriage adapted to support a lamp within said casing, means supporting and guiding said carriage for forward and rearward movement with reference to said lamp casing, said mechanism 5 housing having front and rear walls provided with horizontally extending slots, a focusing lever within said housing pivotally mounted on a substantially vertical axis, said lever having oppositely extending arms projecting through said

horizontally extending slots, and an operative interconnection between said focusing lever and said lamp carriage embodying a third arm on said lever extending substantially at right angles to said first mentioned arms, and a pin and slot 5 connection between said third arm and the carriage.

CARL R. ERICKSON.
